HAT WELL

Joseph Polite, Detroit, Mich.

Application August 9, 1947, Serial No. 767,700

9 Claims. (Cl. 223—84)

1

This invention relates to hat holders or hat wells.

One object of this invention is to provide a hat well capable of conveniently holding a hat and also preserving the shape of the brim.

Another object is to provide a hat well having a crown receptacle formed in two parts, one of which swings outward relatively to the other so that the hat is easily inserted and removed.

Another object is to provide a hat well, as set forth in the preceding objects, wherein the hat is protected from dust and is kept in form by brim-shaping members which are pressed toward one another on opposite sides of the brim.

Another object is to provide a hat well having a divided crown receptacle adapted to receive various sizes of hats and which permits air to enter and circulate inside the crown and thus maintain it in a clean and sanitary condition.

Another object is to provide a hat well having complementary brim-shaping members, one of which is movable away from the other, and a divided crown receptacle attached thereto, one of the halves of which automatically swings outward as one of the hat-shaping members is moved away from the other.

Another object is to provide a hat well, as set forth in the preceding objects, wherein the crown receptacle halves are detachable so as to permit storing or shipping the device in compact space.

Another object is to provide a hat well, as set forth in the preceding objects, wherein one of the brim-shaping members is urged toward the other by a pair of spring-pressed arms, the ends of which are fastened to the center of one of the brim-shaping members so as to obtain an even distribution of pressure upon the brim.

In the drawing:

Figure 1 is a top plan view of a hat well, according to a preferred form of the invention, with one of the brim shaping members and a portion of the spring cover broken away to disclose the construction beneath it;

Figure 2 is a central vertical section along the line 2—2 in Figure 1, with the end of the handle in side elevation;

Figure 3 is a vertical cross-section along the line 3—3 in Figure 1;

Figure 4 is a right-hand end elevation of the handle of the hat well shown in Figure 1;

Figure 5 is a fragmentary top plan view of the crown receptacle at the forward end thereof, showing the overlapping joint between the halves;

2

Figure 6 is a fragmentary top plan view of the actuating portion of the movable half of the crown receptacle; and

Figure 7 is a cross section through the crown receptacle and brim-shaping members taken along the line 7—7 in Figure 1.

Referring to the drawings in detail, Figures 1 and 2 show a hat holder or hat well, generally designated 10, as consisting generally of a handle structure 11, an upper brim-shaping member 12, stationary and movable lower brim-shaping halves 13 and 14 respectively, corresponding stationary and movable crown receptacle halves 15 and 16 respectively, and an adjustable hat interior shaping device 17. The upper brim-shaping member 12 is of annular form, whereas the stationary brim-shaping member 13 is of semi-annular form and has a bracket portion 18 secured by the screws 18a to the handle structure 11. The movable lower brim-shaping member 14 is likewise of semi-annular form and is provided at one end with a rearwardly-extending arm 19 which is pivotally mounted upon a pivot pin or stud 20 secured to the handle structure 11. The arm 19 extends rearwardly beyond the pivot stud 20 and is provided with an upstanding flange 21. The stud 20 passes through holes 22 and 23 in the arm 19 and handle structure 11 respectively (Figures 2 and 6). A coil spring 24 encircles the pivot stud 20 and has one of its ends 25 resting against an anchor pin 26 secured to the stationary lower brim-shaping member 13 and has its other end 27 engaging the flange 21. By this means, the movable lower brim-shaping member 14 is resiliently urged toward the stationary brim-shaping member 13.

The upper brim-shaping member 12 is provided with a pair of hinge brackets 28 located approximately on its cross-diameter and serving to pivotally hold the outer ends 29 of parallel spring arms 30 each consisting of outer and inner arm portions 31 and 32 respectively. The outer arm portions 31 are anchored at their ends in notches 33 (Figure 3) in the opposite ends of a shaft 34 which is journaled in the aligned bores 35 in angle brackets 36 mounted on and riveted to the handle structure 11. The ends 37 of the outer arms 31 are bent angularly on opposite sides of the notches 33 so as to retain them in these notches. The inner spring arms 32, on the other hand, terminate in coil spring portions 38, the opposite ends 39 of which pass through holes 40 in the handle structure 11 and are bent as at 41 (Figure 2) to anchor them in position. The spring portions 38 and the shaft 34 which

they encircle are concealed by a spring cover 42 which is secured by the screws 43 to the angle brackets 36. The spring cover 42 has end slots 44 for the passage of the inner spring arm portions 32 and also has a central slot 45 through which passes a hub 46 secured as by the set screw 47 to the shaft 34. The hub 46 is provided with spaced ears 48 bored to receive a pivot pin 49 which likewise passes through a tongue 50 on the lower end of a swinging handle 51 having stop flanges 52 swinging into abutting engagement with the ears 48. By this means, the handle 51 can swing forward into the dotted-line position to the left thereof in Figure 2 without rotating the shaft 34, yet rotates the shaft 34 when swung into the right-hand dotted line position in Figure 2. This construction permits the handle 51 to be swung into a flat position after a hat has been inserted. At the same time, however, the swinging of the handle 51 rearwardly (Figure 2) rotates the shaft 34 in a clockwise direction to swing the parallel arms 39 upward, carrying with them the upper brim-shaping member 42.

Mounted on the shaft 34 is a radial pin 53 which when the shaft 34 is rotated by means of the handle 51, engages the flange 21 and swings the lower movable brim-shaping member 14 outward away from the stationary member 13. The pin 53 and flange 21, therefore, act as a cam and cam follower respectively. The outward swinging of the brim-shaping member 14 carries with it the crown receptacle half 16 which is provided with a flange 54 seated under a retaining strip 55 (Figure 7) which is welded or otherwise secured to the under side of the member 14. Similarly, the upper edge of the stationary crown receptacle half 15 is provided with a flange 56 seated under a similar retaining strip 57 likewise welded or otherwise secured to the underside of the stationary lower brim-shaping member 13.

The crown receptacle halves 15 and 16 together form a cup-shaped receptacle for the crown of the hat H, the brim of which is held between the brim-shaping members 12, 13 and 14. The receptacle halves 15 and 16 may be removed from their retaining strips 55, 57 in order to nest them for storage or shipment. The joints or gaps 58 (Figure 5) between the halves 15, 16 are covered by vertical lips or flanges 59.

The handle structure 11 is provided with an arcuate flange 60 adjacent the rearward ends of the halves 15, 16 and integral with this flange is a slightly rounded boss 61 (Figure 2) which engages the underside of the stationary brim-shaping member 13 and fills in the space between it and the handle structure 11. The brim-shaping members 12, 13 and 14 are either flat or convexo-concave according to the shape of the brim of the hat which the device is intended to receive.

In order to shape the interior of the hat H in the vicinity of the sweatband thereof, the upper brim-shaping member 12 is provided with a pair of upstanding ears 62 located at the forward and rearward ends of the oval aperture 63 in the brim-shaping member 12. The ears 62 are bored as at 64 to slidably receive the outer ends of oppositely-threaded rods 65 and 66 respectively, the inner ends of which are threaded into the oppositely-threaded ends of the bore 67 in an adjusting collar 68 (Figure 2). The rods 65 and 66 are flanged, as at 69, and secured to these flanges are arcuate members 70 which engage the crown of the hat H in the vicinity of the sweatband. The rotation of the collar 68 causes the arcuate members 70 to move toward or away

from one another so as to fit different sizes of hat.

The handle structure 11 is provided with a handle portion 71 which is drilled transversely as at 72 (Figure 4) to receive a pivot pin 73. The latter passes through the eyes 74 formed on the lower ends of a U-shaped bail or latch 75, the upper portion of which is adapted to snap into a notch 76 formed between ridges 77 on the end of the swinging handle 51, when the latter is pulled into a position parallel with the handle portion 71.

In the operation or use of the invention, to insert a hat, the operator swings the handle 51 upward from its left-hand dotted position to its vertical solid-line position, whereupon the stop flanges 52 (Figures 2 and 3) engage the ears 48 in abutting relationship. Further swinging of the handle 51 to the right into the right-hand dotted line position rotates the shaft 34 through approximately 90 degrees and swings the spring arms 39 upward. This raises the upper brim-shaping member 42 to a vertical position indicated by the dotted lines at the upper end of the handle 51. The bail or latch 75 may now be snapped over the outer ridge 77 into the notch 76, holding the parts in this position.

In the meantime, the rotation of the shaft 34 has caused the pin 53 to engage the obliquely-directed flange 21 on the end of the arm 19 of the movable lower brim-shaping member 14, swinging the latter outward around the pivot stud 26 and consequently separating the crown receptacle halves 15 and 16, thereby making it easier to insert the hat. The hat H is then inverted and dropped into the space between the hat well halves 15 and 16. The operator then swings the bail 75 out of the notch 76, releasing the handle 51. The coil springs 32, which have been compressed while raising the spring arms 39, now swing the latter downward and with them the upper brim-shaping member 42. At the same time, the consequent rotation of the shaft 34 swings the pin 53 upward out of engagement with the flange 21 and the coil spring 24 swings the movable lower brim-shaping member 14 and receptacle half 16 inward toward the stationary brim-shaping member 13 and receptacle half.

The collar 68 is now rotated in one direction or the other so as to bring the arcuate members 70 into engagement with the sweatband of the hat H, holding it firmly in position and preventing distortion thereof. The handle 51 may then be swung downward to the left (Figure 2) into its dotted line position so as to make the device more compact.

What I claim is:

1. A hat well comprising a support having connected thereto a hat crown receptacle, a pair of relatively movable complementary brim-shaping structures engageable with the opposite surfaces of a hat brim, one of said structures including a portion movable laterally relatively to the remainder thereof, one of said structures being hinged to said support to swing toward and away from the other structure, a handle pivotally mounted on said support, and mechanism operatively connecting said handle to said structures and responsive to the swinging of said handle to move said structures away from one another.

2. A hat well comprising a support having connected thereto a hat crown receptacle, a pair of relatively movable complementary brim-shaping structures engageable with the opposite surfaces of a hat brim, one of said structures including a

portion movable laterally relatively to the remainder thereof, one of said structures being hinged to said support to swing toward and away from the other structure, a handle pivotally mounted on said support, and mechanism operatively connecting said handle to said structures and responsive to the swinging of said handle to move said structures away from one another and also to move the movable portion of one of said structures laterally away from the remainder thereof.

3. A hat well comprising a support having connected thereto a hat crown receptacle and a pair of relatively movable complementary brim-shaping structures engageable with the opposite surfaces of a hat brim, one of said structures including a portion movable laterally relatively to the remainder thereof, said crown receptacle also having a portion movable laterally relatively to the remainder thereof.

4. A hat well comprising a support having connected thereto a hat crown receptacle and a pair of relatively movable complementary brim-shaping structures engageable with the opposite surfaces of a hat brim, one of said structures including a portion movable laterally relatively to the remainder thereof, said crown receptacle also having a portion connected to the laterally movable portion of said structure and movable laterally relatively to the remainder thereof.

5. A hat well comprising a support having connected thereto a hat crown receptacle, a pair of relatively movable complementary brim-shaping structures engageable with the opposite surfaces of a hat brim, one of said structures including a portion movable laterally relatively to the remainder thereof, one of said structures being hinged to said support to swing toward and away from the other structure, a handle pivotally mounted on said support, and mechanism operatively connecting said handle to said structures and responsive to the swinging of said handle to move said structures away from one another, said crown receptacle also having a portion movable laterally relatively to the remainder thereof.

6. A hat well comprising a support having connected thereto a hat crown receptacle, a pair of relatively movable complementary brim-shaping structures engageable with the opposite surfaces of a hat brim, one of said structures including a portion movable laterally relatively to the remainder thereof, one of said structures being hinged to said support to swing toward and away from the other structure, a handle pivotally mounted on said support, and mechanism operatively connecting said handle to said structures and responsive to the swinging of said handle to move said structures away from one another, said crown receptacle also having a portion connected to the laterally movable portion of said structure and movable laterally relatively to the remainder thereof.

7. A hat well comprising a support having a pair of complementary brim-shaping structures engageable with the opposite surfaces of a hat brim, a shaft rotatably mounted on said support and connected to one of said structures, a handle connected to said shaft to rotate said shaft, the other structure having a stationary portion connected to said support and a movable portion movable laterally relatively to said stationary portion, and mechanism connecting said movable portion to said shaft for moving said movable portion away from said stationary portion in response to the rotation of said shaft.
8. A hat well comprising a support having a pair of complementary brim-shaping structures engageable with the opposite surfaces of a hat brim, a shaft rotatably mounted on said support and connected to one of said structures, a handle connected to said shaft to rotate said shaft, the other structure having a stationary portion connected to said support and a movable portion movable laterally relatively to said stationary portion, mechanism connecting said movable portion to said shaft for moving said movable portion away from said stationary portion in response to the rotation of said shaft and a hat crown receptacle having stationary and laterally-movable portions connected respectively to said stationary and laterally-movable brim-shaping structure portions for motion therewith.

9. A hat well comprising a support having a pair of complementary brim-shaping structures engageable with the opposite surfaces of a hat brim, a shaft rotatably mounted on said support and connected to one of said structures, a handle connected to said shaft to rotate said shaft, the other structure having a stationary portion connected to said support and a movable portion movable laterally relatively to said stationary portion, mechanism connecting said movable portion to said shaft for moving said movable portion away from said stationary portion in response to the rotation of said shaft and a hat crown receptacle having stationary and laterally-movable portions connected respectively to said stationary and laterally-movable brim-shaping structure portions for motion therewith, said receptacle portions being detachably secured to the corresponding portions of the brim-shaping structure to which they are attached.
